J. A. BOEHRINGER

COMBINED STRAP AND ARM FOR LIGHTING FIXTURES OR SIMILAR ARTICLES

Filed March 3, 1928

John A. Boehringer
INVENTOR.

UNITED STATES PATENT OFFICE.

JOHN A. BOEHRINGER, OF SPRINGFIELD, NEW YORK, ASSIGNOR TO STAR CHANDELIER CO., INC., OF NEW YORK, N. Y., A CORPORATION OF NEW YORK.

DESIGN FOR A COMBINED STRAP AND ARM FOR LIGHTING FIXTURES OR SIMILAR ARTICLES.

Application filed March 3, 1928. Serial No. 25,655. Term of patent 3½ years.

To all whom it may concern:

Be it known that I, JOHN A. BOEHRINGER, a citizen of the United States, residing at 145-85 Aberdeen Street, Springfield, Long Island, in the county of Queens and State of New York, have invented a new, original, and ornamental Design for a Combined Strap and Arm for Lighting Fixtures or similar articles, of which the following is a specification, reference being had to the

accompanying drawing, forming part thereof.

The figure is a perspective view of a combined strap and arm for lighting fixtures or similar articles showing my new design.

I claim:

The ornamental design for a combined strap and arm for lighting fixtures or similar articles, as shown.

JOHN A. BOEHRINGER.
